(57) **CLAIM**

We claim the ornamental design for a display panel with an animated graphical interface, as shown and described.

DESCRIPTION

FIG. 1 is a front view of a display panel with an animated graphical interface showing a first image in a sequence showing our new design;

FIG. 2 is a second image thereof;

FIG. 3 is a third image thereof; and,

FIG. 4 is a fourth image thereof.

The outer broken lines in the drawings show a display screen that forms no part of the claimed design. The other broken lines in the drawings, including the thick and thin broken lines, show portions of the graphical interface that form no part of the claimed design. Moreover, the subject matter in this patent includes a process or period in which an image changes into another image. This process or period forms no part of the claimed design.
